UNITED STATES PATENT OFFICE.

JOHN NIERODKA, OF CHICAGO, ILLINOIS.

GEOMETRICAL PUZZLE.

Application filed March 11, 1925. Serial No. 14,713.

To all whom it may concern:

Be it known that I, JOHN NIERODKA, a citizen of Poland, residing at Chicago, in the county of Cook and State of Illinois, have invented certain new and useful Improvements in Geometrical Puzzles, of which the following is a specification.

The invention relates to geometrical puzzles consisting of a plurality of regular polygons, the main object of which is to construct a comparatively large number of regular geometrical figures, employing comparatively few polygons, by properly arranging and laying said polygons edgewise.

Another object of the invention is to provide seven regular polygons out of which five regular geometrical figures may be selectively constructed by arranging said polygons and laying them edgewise.

A further object of the invention is to provide a puzzle consisting of a number of regular polygons, which, when properly arranged and laid edgewise, will selectively form a square, a rectangle, a hexagon, an isosceles triangle, and a rhomboid.

A still further object of the invention is the provision of an article of manufacture consisting of a plurality of polygonal blocks, which, when properly arranged will selectively form a plurality of blocks of definite geometrical configuration.

In the drawing, wherein like designating characters refer to corresponding parts throughout the several views, Fig. 1 illustrates a square; Fig. 2 shows a rectangle; Fig. 3 shows a hexagon; Fig. 4 illustrates an isosceles triangle; and Fig. 5 represents a rhomboid.

All of the geometrical figures hereinabove named and shown by the respective views on the drawing are formed by the same seven polygons or polygonal blocks which have regular geometrical shapes. Said polygons comprise two isosceles triangles 1 and 2 of like dimensions; two isosceles triangles 3 and 4 of like dimensions, said triangles having a size larger than the first mentioned two triangles; one square 5; one square 6, said square being larger than the first named square; and one rhomboid 7.

The polygonal blocks hereinabove enumerated are made of wood, card-board, metal or any other suitable material, and for the

sake of neatness and appearance the thickness of the polygons should be uniform.

When the polygons are disarranged they will present to the uninitiated a rather difficult problem to arrange them into various geometrical figures hereinabove specified and shown on the drawing, and will provide a useful and educational amusement for children as well as for adults.

For the purposes of sale the polygonal blocks may be arranged into any one of the figures illustrated in the drawing and marketed in a box of corresponding shape.

The invention may also be used as a charm or watch fob, and in that latter use of the invention a suitable casing of a shape of any one of the figures shown in the drawing may be provided for inclosing therewith the polygonal blocks in arranged formation corresponding to the shape of the casing.

While there is herein shown and described the preferred embodiment of the present invention, it is nevertheless understood that minor changes may be made therein without departing from the spirit and scope of the invention as claimed.

What I claim as new is:

1. A seven figure puzzle comprising two squares, four triangles, and a rhomboid, which when placed together edge-wise will form a plurality of geometrical figures, including a rectangle.

2. A seven figure puzzle comprising two squares, four triangles, and a rhomboid, which when placed together edge-wise will form a plurality of geometrical figures, including a hexagon.

3. A seven figure puzzle comprising two squares, four triangles, and a rhomboid, which when placed together edge-wise will form a plurality of geometrical figures, including a triangle.

4. A seven figure puzzle comprising two squares, four triangles, and a rhomboid, which when placed together edge-wise will form a plurality of geometrical figures, including a rhomboid.

5. A seven figure puzzle comprising two squares, four triangles, and a rhomboid, which when placed together edge-wise will form a plurality of geometrical figures, including a square and a rectangle.

6. A seven figure puzzle comprising two squares, four triangles, and a rhomboid, which when placed together edge-wise will form a plurality of geometrical figures, including a square and a hexagon.

7. A seven figure puzzle comprising two squares, four triangles, and a rhomboid, which when placed together edge-wise will form a plurality of geometrical figures, including a square and a triangle.

8. A seven figure puzzle comprising two squares, four triangles, and a rhomboid, which when placed together edge-wise will form a plurality of geometrical figures, including a square and a rhomboid.

9. A seven figure puzzle comprising two squares, four triangles, and a rhomboid, which when placed together edge-wise will form a plurality of geometrical figures, including a square, a rectangle, and a hexagon.

10. A seven figure puzzle comprising two squares, four triangles, and a rhomboid, which when placed together edge-wise will form a plurality of geometrical figures, including a square, a rectangle, and a triangle.

11. A seven figure puzzle comprising two squares, four triangles, and a rhomboid, which when placed together edge-wise will form a plurality of geometrical figures, including a square, a rectangle, and a rhomboid.

12. A seven figure puzzle comprising two

squares, four triangles, and a rhomboid, which when placed together edge-wise will form a plurality of geometrical figures, including a square, a rectangle, a hexagon, and a triangle.

13. A seven figure puzzle comprising two squares, four triangles, and a rhomboid, which when placed together edge-wise will form a plurality of geometrical figures, including a square, a rectangle, a hexagon, a triangle, and a rhomboid.

14. A seven figure puzzle comprising one smaller and one larger square and four triangles, the area of the smaller square being equal to the area of one pair of said triangles, and the area of the larger square being equal to the area of the other pair of said triangles, said polygons when placed together edgewise being adapted to form a plurality of geometrical figures.

15. A seven figure puzzle comprising one rhomboid, one smaller and one larger square, and four triangles, the area of the smaller square being equal to the area of one pair of said triangles, and the area of the larger square being equal to the area of the other pair of said triangles, said polygons when placed together edgewise being adapted to form a plurality of geometrical figures.

In testimony whereof I affix my signature.
JOHN NIERODKA.
